(57) **CLAIM**

The ornamental design for a display screen or portion thereof with animated graphical user interface, as shown and described.

DESCRIPTION

FIG. 1 is a front view of an image in a sequence for a display screen or portion thereof with animated graphical user interface;

FIG. 2 is a front view of another image thereof;

FIG. 3 is a front view of another image thereof; and,
FIG. 4 is a front view of another image thereof.

The appearance of the animated graphical user interface sequentially transitions between the images shown in FIGS. 1 to 3 in a first embodiment, and FIGS. 2 to 4 in a second embodiment. The process or period in which one image transitions to another forms no part of the claimed design. The outermost broken line rectangle illustrates a portion of a display screen and forms no part of the claimed design. The remaining broken lines represent features of the graphical user interface that form no part of the claimed design.
